UNITED STATES PATENT OFFICE.

PHILEMON MARKLEY, OF CANTON, ILLINOIS.

IMPROVEMENT IN FILTERING-CISTERNS.

Specification forming part of Letters Patent No. **41,850**, dated March 8, 1864.

To all whom it may concern:

Be it known that I, PHILEMON MARKLEY, of Canton, in the county of Fulton and State of Illinois, have invented a new and useful Improvement in Filtering-Cisterns; and I do hereby declare that the following is a full and exact description thereof, reference being had to the accompanying drawing, and to the letters and figures of reference thereon.

The nature of my invention consists in building the cistern proper, A, in the form of a hollow globe or sphere, with the water-chamber B directly above the cistern, giving a large filtering-surface, and so arranging the water-chamber with the cistern that both shall rest upon the same base best adapted to resist pressure from without, and thus prevent cracking from pressure or settling by weight.

To enable others skilled in the art to make such a cistern, I will proceed to describe its construction and operation.

I construct my cistern by excavating a circular pit in the ground to the depth desired for the point marked 3, from which half the globe will be below and half above that point when completed. With a revolving center post and radius, the attached end of the radius at the point 3, I determine the outline of the hollow sphere necessary to form a perfect half-globe when the brick are laid upon the surface of the lower excavation. I build the lower half of the globe an eight-inch brick wall, and from the height, equal to the center, (marked 3,) I build a four-inch perpendicular circular wall, resting on outer half of base, and as high as center, (marked 4,) and cement the perpendicular wall. I then build the upper

half of the globe-cistern wall four inches in thickness and resting on inside half of base-wall, "laying in" lead pipe for pump and leaving a circular opening at top sixteen inches in diameter; then cement the lower half only of the globe and lay a flat stone in cement over the opening. I then cover the upper wall of globe with sand and put a layer of charcoal and of sand, as shown in drawing. Covering the sand with boards upon which to stand, I then lay the arched or vaulted roof-wall over the water-chamber, leaving a circular opening at top of sixteen inches diameter, and build up a circular neck, as shown, and cement the inside of roof of water-chamber and neck. As the walls are being built, I lay in the necessary pipes for pump, inlet and outlet.

The water from inlet-pipe is so directed as to strike the flat stone, and then it filters through the two-inch layer of sand, through four-inch layer of charcoal, through the lower stratum of sand, and finally through brick forming upper half of globe-cistern wall.

What I claim as my invention, and desire to secure by Letters Patent, is—

A filtering-cistern in the form of a hollow globe, with the chamber for unfiltered water directly above the cistern, thereby giving a filtering surface equal to the circumference of the water-chamber, with the water chamber and cistern having a common base—to wit, the lower half of an eight-inch globe wall.

PHILEMON MARKLEY.
